United States Patent Office

Des. 189,004
Patented Oct. 11, 1960

189,004

COMBINED CAN OPENER AND SPOUT

Frederick Abel, Dayton, Ohio, assignor to The Huffman Manufacturing Company, Dayton, Ohio, a corporation of Ohio

Filed Oct. 1, 1959, Ser. No. 57,755

Term of patent 14 years

(Cl. D58—26)

FIG-1

FIG-3

Fig. 1 is a side elevational view of a combined can opener and spout embodying my new design;

Fig. 2 is a bottom plan view thereof; and

Fig. 3 is a top plan view thereof.

I claim:

The ornamental design for a combined can opener and spout, substantially as shown.
